UNITED STATES PATENT OFFICE.

JOSIAH SMITH, OF LEEDS, ENGLAND.

MACHINE FOR MOLDING SOAP AND THE LIKE SUBSTANCES.

1,384,571.

Specification of Letters Patent. Patented July 12, 1921.

Application filed November 16, 1920. Serial No. 424,363.

To all whom it may concern:

Be it known that I, JOSIAH SMITH, a subject of the King of Great Britain, residing at Leeds, in the county of York, England, 5 have invented certain new and useful Improvements in Machines for Molding Soap and the like Substances, of which the following is a specification.

This invention relates to machines for 10 molding soap and the like substances (hereinafter termed "soap") into bars or slabs, and has reference to that kind of machine wherein hot liquid soap is drawn down into smooth metal molds of tubular formation 15 by way of their upper open ends from a supply tank situated thereover and in which, on the contents of the molds having become set by cooling, the solidified bars or slabs of soap are ejected upwardly from the molds. 20 Hitherto, the tubular molds of the soap-molding machine have been fitted with plungers which are lowered to draw the hot liquid soap from the supply tank into the molds and are raised to eject the solidified 25 bars or slabs of soap from the molds.

This known plunger device however has the effect of rendering the soap-molding operation slow and tedious; and the object of this present invention is to provide the tubular molds of soap-molding machines with an improved charging and discharging mechanism, the arrangement being such as to enable the soap-molding operation to be carried on in a much more speedy and efficient manner than heretofore.

According to my invention, the tubular molds of the soap-molding machine are carried in a framing and provided at their upper open ends with a supply tank containing the hot liquid soap as before; but instead of employing mechanically operated plungers in the molds, they are fitted with pistons which are lowered to draw the hot liquid soap from the supply tank into the 40 molds through the medium of a vacuum set up within the molds beneath their pistons and, after the cooling of the contents of the molds, are raised through the medium of compressed air passed into the molds beneath their pistons to eject the solidified bars or slabs of soap from the molds.

I will now proceed to describe the invention with reference to the example of construction shown in the accompanying drawings; wherein:—

Figures 1 and 2 are respectively a part

sectional elevation and a plan view of a soap-molding machine, having its battery of tubular molds for molding bars of soap fitted with my improved charging and discharging mechanism; and Fig. 3 is an enlarged sectional elevation of one of the tubular molds of the machine shown at Figs. 1 and 2. Figs. 4 and 5 are similar views to Fig. 3 showing slight modifications of construction; and Fig. 6 is a sectional elevation and a plan view of a tubular mold for molding slabs of soap fitted with my improved charging and discharging mechanism.

Referring particularly to Figs. 1, 2 and 3 of the drawings, 1 is a framing within which is mounted a vertically arranged battery of tubular molds 2 designed for forming bars of soap, the said framing 1 being provided at its upper part over the upper 75 open ends of the tubular molds 2 with a supply tank 3 adapted to act as a container for the hot liquid soap. The tubular molds 2 are fitted with vertically slideable pistons 4, while the lower ends of the tubular molds 2 are closed by plates 5 carrying short vertical pipes 6 by which communication is established between the tubular molds 2 and a series of longitudinal pipes 7 leading into a transverse pipe 8 of a main pipe 9 joined 85 on the one hand by a branch pipe 10 to a steam ejector 11 and on the other hand by a branch pipe 12 to a container casing 13 of an air-compressor engine 14, the steam ejector branch pipe 10 being fitted with a cut-off 90 valve 15 and the air-compressor branch pipe 12 with a cut-off valve 16.

Assuming the valves 15, 16 to be closed and the pistons 4 to be situated at the upper ends of the tubular molds 2 as in Fig. 95 1; a quantity of hot liquid soap sufficient to fill the entire battery of tubular molds 2 is first poured into the supply tank 3, when on opening the valve 15 the steam ejector 11 has the effect of exhausting the air from 100 the tubular molds 2 by way of the pipes 10, 9, 8, 7 and 6, whereby a vacuum is set up within the tubular molds 2 beneath their pistons 4 which thus fall and in doing so draw down the hot liquid soap from the supply tank 3 into the tubular molds 2. The contents of the tubular molds 2 are then allowed to set by cooling; after which, on the valve 15 having been closed so as to cut off the steam ejector 11, the valve 16 is 110 opened to admit compressed air from the compressor casing 13 along the pipes 12, 9,

8, 7 and 6 to within the tubular molds 2 beneath their pistons 4 which thus become raised and eject the solidified bars of soap upwardly from the tubular molds 2.

5 The battery of tubular molds 2 having been emptied, the operations above described are repeated for each lot of soap bars subsequently molded; and it will be seen that in employing the above described charging and 10 discharging mechanism, the soap-molding operation is rendered capable of being carried on in a much more speedy and efficient manner than heretofore.

Referring particularly to Fig. 4 of the 15 drawings, the tubular mold 2 is formed near its upper end with a side aperture 17 fitted with a flap valve 18 which during the down stroke of the piston 4 keeps the aperture 17 closed, but which on the up stroke of the 20 piston 4 limits the upward movement of the latter by acting as a relief to the compressed air immediately the piston 4 has passed the aperture 17.

In Fig. 5 of the drawings, the upward 25 control of the piston 4 in the tubular mold 2 is effected by means of an attached chain 19; otherwise the action is similar to that described with reference to Fig. 4.

Referring particularly to Fig. 6 of the 30 drawings, the tubular mold 2 is of oblong cross-section fitted with a piston 2 of a corresponding shape for enabling the soap to be molded into slabs; the charging and discharging of the said mold 2 being similar to 35 that of the molds 2 previously described.

What I claim as my invention and desire to secure by Letters Patent is:—

1. A soap-molding machine of the kind specified; comprising in combination, a 40 framing, tubular molds carried by the framing, a tank situated on the framing for supplying hot liquid soap to the upper open ends of the tubular molds, slidable pistons within the tubular molds, and means for setting up a vacuum within the tubular molds to lower the slidable pistons and draw the 45 hot liquid soap from the supply tank into said tubular molds, together with means for supplying compressed air to the tubular 50 molds to raise the slidable pistons and eject the solidified bars or slabs of soap from said tubular molds.

2. A soap-molding machine of the kind specified; comprising in combination, a 55 framing, tubular molds carried by the framing, a tank situated on the framing for sup-

plying hot liquid soap to the upper open ends of the tubular molds, slidable pistons within the tubular molds, and a steam ejector adapted to set up a vacuum within the 60 tubular molds to lower the slidable pistons and draw the hot liquid soap from the supply tank into said tubular molds, together with a compressor adapted to force compressed air into the tubular molds to raise the slidable pistons and eject the solidified bars or slabs of soap from said tubular molds.

3. A soap-molding machine of the kind specified; comprising in combination, a 70 framing, tubular molds carried by the framing, a tank situated on the framing for supplying hot liquid soap to the upper open ends of the tubular molds, slidable pistons within the tubular molds, a steam ejector 75 adapted to set up a vacuum within the tubular molds to lower the slidable pistons and draw the hot liquid soap from the supply tank into said tubular molds, and a compressor adapted to force compressed air into 80 the tubular molds to raise the slidable pistons and eject the solidified bars or slabs of soap from said tubular molds, together with means for controlling the upward movement of the slidable pistons within the tu- 85 bular molds.

4. A soap-molding machine of the kind specified; comprising in combination, a 90 framing, tubular molds carried by the framing, a tank situated on the framing for supplying hot liquid soap to the upper open ends of the tubular molds, slidable pistons within the tubular molds, a steam ejector adapted to set up a vacuum within the 95 tubular molds to lower the slidable pistons and draw the hot liquid soap from the supply tank into said tubular molds, and a compressor adapted to force compressed air into the tubular molds to raise the slidable pistons and eject the solidified bars or slabs of 100 soap from said tubular molds, together with flexible connections between the slidable pistons and the bases of the tubular molds for controlling the upward movement of said 105 slidable pistons within said tubular molds.

In witness whereof I have hereunto set my hand in the presence of two witnesses.

JOSIAH SMITH.
